COMBINED ACCESSORY BAG AND SKI BOOT TREE

Norman W. Selnes, 3725 W. Outer Drive, Detroit, Mich.

Filed Apr. 13, 1965, Ser. No. 84,767

Term of patent 14 years

(Cl. D87—5)

FIG. 1 is a front perspective view of a combined accessory bag and ski boot tree showing my new design; and

FIG. 2 is a top plan view; and

FIG. 3 is a bottom view; and

FIG. 4 is a side elevational view; and

FIG. 5 is a rear perspective view thereof, on a reduced scale.

I claim:

The ornamental design of a combined accessory bag and ski boot tree, substantially as shown.
